UNITED STATES PATENT OFFICE.

WILLIAM L. BELT, OF WASHINGTON, DISTRICT OF COLUMBIA.

SHUTTER-WORKER.

SPECIFICATION forming part of Letters Patent No. 283,194, dated August 14, 1883.

Application filed April 5, 1883. (No model.)

To all whom it may concern:

Be it known that I, WILLIAM L. BELT, a citizen of the United States, residing at Washington, in the District of Columbia, have invented 5 certain new and useful Improvements in Shutter-Working Devices, of which the following is a specification, reference being had therein to the accompanying drawings.

This invention relates to improvements in 10 shutter-working devices; and it consists in certain devices applied to the shutter and also to the sill of a window, whereby the shutters can be opened, closed, or bowed, and held firmly in either position without raising the sash, all of 15 which will be hereinafter more particularly described, and pointed out in the claim.

In the drawings forming part of this specification, Figure 1 represents a plan view of the devices attached to a window-sill and the shutter, which last is shown in horizontal section. 20 Fig. 2 represents two modifications of the clamping device. Fig. 3 represents the operating-levers detached from the window-frame and shutter. Fig. 4 is a modification of the 25 brace-bar. Figs. 5 and 6 are details of the cam-groove, plates, and the fulcrum for the working-bar.

A represents the bottom rail of a shutter in 30 horizontal section in Fig. 1, represented as being closed against the sill of the window. In the broken lines two other positions of the shutter are shown—one with the shutter half open and the other with the shutter full open—in each of which positions the operative devices 35 are shown in corresponding lines.

B is the window-frame jamb. C is the inside 40 sill or sash-stop. D is the main sill of the window-frame, and D' represents the thickness of the sash-rail.

45 On the lower edge of the inside of the bottom rail of a window-shutter, A, is secured a rod, A', by means of two brackets, a a, which are screwed to the shutter, as seen in Fig. 1. In Fig. 4 is shown a modification, where two rods, a' a', may be used, as will be hereinafter explained.

The shutter A is hung by ordinary Parliament hinges, B'. On the sill D of the frame, 50 near the edge, is a plate, E, screwed down to the sill. In its center is a pivot, e, on which pivot e moves the hub F of a bent lever, F',

having a short arm, F''. The long arm F' is curved at its end, and is bifurcated, as in Fig. 1, and carries within it a friction-roller, f, which is designed to run along the inner side of the 55 rod A', as seen in the end view of the lever F', and also touching the face of the rail of the shutter.

In Fig. 4 is represented a double bar, a' a', which can be used in place of the single bar, in 60 which case the bent lever F' is not bifurcated, but has one or more friction-rollers, as shown in Fig. 4, and also in the end view of the lever in Fig. 3. To the short arm F'' is attached, by a pivot, f', a connecting-lever, G, 65 which is attached at its other or free end to the clamping-screw H, as seen in Fig. 2, by the threaded shank h, or by the round shank h' of the modified clamp H'. In the first case, H, a female thread is cut in the free end of G, so 70 that by turning the screw-clamp H the lever G is closely bound up to the plate I above it. In the clamp H' there is no screw, but the shank h' is riveted below G at h'', and between G and plate I is an eccentric, i, fastened to the shank 75 h', so that a very slight turn will fasten it by binding the plate I and lever G.

I is a cap-plate, having within it a horseshoe-formed groove, in which moves the shank h or h', as either clamp may be used, and on top is 80 the clamp H or H', as seen in Fig. 2. This plate I covers a mortise in sill C, wherein the end of lever G is free to move inwardly and around, according to the form of the groove. In the edge of plate I is an opening for the lever 85 G to enter, and that orifice is formed as shown in Fig. 6, where the points k act as fulcrums for the bearing of the lever G as it moves in or out of the mortise.

In Figs. 1 and 3 a slot, g, is shown in lever 90 G, and a pin, i', projects from the front of the bottom part of plate I, through this groove g, as shown in the plan and section of plate I, Fig. 5. The object of this pin i' is to form a fulcrum in the groove g for the lever G, and 95 when thus placed the horseshoe-groove in plate I must be widened to correspond with the movements of the lever G, as in Fig. 5.

When the frame of the window is so constructed that sill C is below the sill D, then a 100 box and plate, I, must be constructed as shown in Fig. 5. A cap-plate, I', is used to cover the

horseshoe-groove in I to prevent the outside air passing from under the sash and into the room, and also to keep out the dust from the mortise.

To open the shutter, loosen the clamp-screw 5 H and move it from its position at No. 1 along the groove to No. 2, when the shuttle will be half open, as seen in short broken lines. When the clamp H has passed to No. 3, the shutter will have passed back against the wall, as seen 10 in long and short broken lines. The broken lines of the operating-levers F', F'', and G show the different positions of these parts. At any desired position of the shutter it can be retained there by tightening the clamp H. The lower 15 edge of the sash must be cut out in accordance with the movements of the lever G. All the motions of the shutter are controlled by the clamp H, which acts as a handle to the lever G, and, being inside of the sash, it is not required 20 to raise the sash to open, close, or bow the shutter to any desired angle.

The lever G acts as a connecting-bar as well as a lever. When the movement of the bar G is 25 to or fro in the straight parts of the groove in I, then G is a connecting-bar to pull or shove upon the short arm F'' of the bent lever; but when the handle H moves around the curved

part or the arch of the groove it is evident that the bearing-points k k in Figs. 1 and 6 act as fulcra, or, as in Fig. 5, the pin i' serves the 30 same purpose within the groove g. In either case this is one of the essential features in my invention, and either can be employed to suit the particular frame in any house where one or the other may be best adapted to give sufficient leverage to operate the device, as in narrow windows the short fulcrum will be sufficient, whereas in wider shutters a longer leverage may be required. 35

I claim—

The combination of the curved lever F' F'', pivoted on the sill of the frame and having a horseshoe-formed groove and one or more friction-rollers at the end, the bar A', connected to a shutter, the connecting bar and lever G, 45 clamp H, and plate I, provided with the fulcrum-bearings, all substantially as and for the purpose described.

In testimony whereof I affix my signature in presence of two witnesses.

WILLIAM L. BELT.
